(57) **CLAIM**

I claim the ornamental design for a karaoke system with stand, as shown and described.

DESCRIPTION

FIG. 1 is a front elevation view of the karaoke system with stand showing my novel design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

The broken lines in FIGS. 1, 2, 3, 4, 5 and 7 illustrate microphones and are for illustrative purposes only and form no part of the claimed design.
